LASTING TOOL

Frank R. Thresh, Beverly, Mass., assignor to
 United Shoe Machinery Corporation, Paterson,
 N. J., a corporation of New Jersey

Application November 9, 1936, Serial No. 109,808

11 Claims. (Cl. 12—110)

This invention relates to portable lasting tools, and more particularly to hand pincers for use in pulling uppers over lasts.

Hand pincers are frequently used, for example, to assist in the lasting of shoes in bed-lasting machines. Such pincers commonly comprise a pair of upper-gripping jaws and a pair of handles which in use extend in approximately horizontal directions over a shoe positioned bottom upward and are swung downwardly by the operator to cause the jaws to pull the upper. An object of the present invention is to provide a construction adapted for convenient use in case, for example, a lasting machine may be provided with a hold-down or other part so formed or arranged over the shoe bottom as to interfere with the use of pincers of the above-mentioned character. A further object is to provide a construction which may be used with equal facility to pull an upper either at the side of a shoe which may face the operator's working position or at the opposite side of the shoe.

With the above and other objects in view, the tool herein shown is so constructed as to pull the upper while extending in a general direction heightwise of the shoe, the upper-gripping jaws being operated both to grip the upper and to pull it heightwise of the shoe by relative movement of a pair of handles. More particularly, the construction shown comprises a member formed to rest on the bottom of the shoe and also to serve as a guide along which the jaws are movable as a unit heightwise of the shoe to pull the upper, and mechanism which by relative movement of the handles first effects relative closing movement of the jaws and then imparts to the jaws their pulling movement. Preferably, as shown, the above-mentioned member is arranged in such relation to the jaws as to serve as a hold-down for the margin of an insole or other shoe bottom part during the pulling of the upper.

The novel features of the invention will now be more particularly described with reference to the accompanying drawing and thereafter pointed out in the claims.

In the drawing,

Fig. 1 shows in elevation a tool in which the invention is embodied and illustrates the relation of the tool to the toe-end portion of a shoe in a lasting machine prior to the gripping and pulling of the upper by the tool; and

Fig. 2 is a view similar to Fig. 1 showing the parts in the positions which they assume in the pulling of the upper, portions of the structure being broken away.

The novel tool is adapted for use to assist in the lasting of a shoe in any bed-lasting machine of well-known type, as well as for other lasting purposes, and the drawing shows a shoe as supported on a toe rest 2 of such a machine in proper relation to toe-lasting wipers 4 which, it will be understood, are used to wipe the upper heightwise of the last and then to wipe its margin inwardly over an insole on the last. The bottom of the shoe is engaged as usual by a hold-down 6 which, however, is herein shown as so constructed and arranged as to interfere with the convenient use of hand-lasting pincers of the character commonly used heretofore. For pulling the upper in different locations about the toe, as is usually desirable before the wipers 4 wipe the margin of the upper inwardly over the insole, the invention provides a tool which includes a member 8 having a depending shank portion 10 the lower end of which is enlarged to provide a foot 12 arranged to rest on the margin of the insole near the edge of the shoe bottom to hold the insole in this location close to the bottom of the last. The shank 10 is formed to serve as a guide for a block 14 on which is secured an upper-gripping jaw 16, and mounted to swing about a pin 18 on this block is a cooperating jaw 20. Both jaws are accordingly movable as a unit in directions substantially perpendicular to the shoe bottom along the guide 10. At its upper end 20 the jaw 20 is bifurcated to straddle the block 14, as shown in Fig. 2, and is provided with a pair of arms 22 which extend respectively along opposite sides of the block in directions transverse to the path of pulling movement of the jaws. 30 Pivots connected to the arms 22 are the lower ends of a pair of links 24 the upper ends of which are pivotally connected to a pair of levers 26 mounted at opposite sides of the member 8 to swing about a pin 28 on this member. The two levers 26 are provided with gear sectors 30 engaged by other gear sectors 32 formed on the lower bifurcated end of a handle 34 which is mounted to swing about a pin 36 on the member 8. Cooperating with the handle 34 is another upwardly extending handle 38 formed integral with the member 8. A spring 40 between these two handles maintains the handle 34 normally in the position indicated in Fig. 1 with the block 14 at the lower limit of its movement in engagement with the foot 12 of the shank 10. A spring 42 the opposite ends of which are mounted in sockets formed respectively in the member 8 and the block 14 assists in holding the block at the lower limit of its movement, this spring be-

ing held in alinement with the two sockets by means of a rod 44 having an enlarged head 46 seated in the socket in the block 14.

It will be understood that in using the tool the operator grasps the two handles 34 and 38 with one hand and positions it, for example, as illustrated in Fig. 1 with the foot 12 resting on the margin of the insole and the margin of the upper between the two jaws. By pressure of his hand 10 on the handles 34 and 38 the operator then swings the handle 34 toward the other handle against the resistance of the spring 40. As the handle 34 starts to move it swings the two levers 26 upwardly and these levers act through the links 24 to 15 swing the jaw 20 into position to grip the margin of the upper against the jaw 16. The spring 42 insures that the two jaws will remain in their lowermost positions until the upper is firmly gripped by the jaws. The upward pull exerted by 20 the links 24 on the arms 22 in response to further movement of the handle 34 then causes both jaws to move as a unit upwardly along the shank 10 against the resistance of the spring 42 to pull the upper heightwise of the last. While thus 25 pulling the upper the operator controls the wipers 4 in the usual manner, pressing them inwardly against the upper at the edge of the insole. After pulling the upper in one location the operator releases it and may then pull it in the same 30 manner in one or more other locations while controlling the upper at or near the edge of the insole by the wipers.

It will thus be seen that in the operation of the illustrated tool both the gripping of the upper by the jaws and the movement of the jaws to pull the upper are effected by the swinging of the handle 34 toward the handle 38, the tool as a whole being maintained in substantially perpendicular relation to the shoe bottom so that the 40 holdown 6 interferes in no way with the operation thereof. It will also be evident that the tool may be used with equal facility to pull the upper at a side of the shoe which faces the operator's working position or to pull it at the opposite 45 side of the shoe or in any other location.

Having described the invention, what I claim as new and desire to secure by Letters Patent of the United States is:

1. A portable lasting tool for pulling an upper manually over a last comprising a pair of relatively movable handles, a pair of upper-gripping jaws, and mechanism for effecting relative movement of said jaws to grip the margin of the upper in response to relative movement of said handles and for thereafter moving the jaws heightwise of the last to pull the upper in response to further relative movement of said handles.

2. A portable lasting tool for pulling an upper manually over a last comprising a pair of relatively movable handles, a pair of upper-gripping jaws, and mechanism for effecting relative closing movement of said jaws to grip the margin of the upper by relative movement of said handles, the jaws being movable by said mechanism heightwise of the last to pull the upper in response to resistance of the upper to further relative closing movement of the jaws.

3. A portable lasting tool for pulling an upper manually over a last comprising a pair of relatively movable handles, a pair of upper-gripping jaws mounted to move as a unit relatively to said handles to pull the upper, and mechanism for effecting relative movement of said jaws to grip the margin of the upper by relative movement 70 of said handles and for thereafter moving the

jaws to pull the upper by further relative movement of said handles.

4. A portable lasting tool for pulling an upper manually over a last comprising a pair of upper-gripping jaws for pulling the upper, a pair of relatively movable handles arranged in such relation to said jaws as to extend generally heightwise of the last in the pulling of the upper, and mechanism for effecting relative movement of said jaws to grip the margin of the upper by 10 relative movement of said handles and for thereafter moving the jaws heightwise of the last to pull the upper by further relative movement of said handles.

5. A portable lasting tool for pulling an upper manually over a last comprising a pair of relatively movable handles, a pair of upper-gripping jaws mounted to move as a unit relatively to said handles to pull the upper, and lever-and-link connections between one of said handles and one 20 of the jaws for effecting relative closing movement of the jaws to grip the margin of the upper and for thereafter moving the jaws to pull the upper.

6. A portable lasting tool for pulling an upper manually over a last comprising a pair of upper-gripping jaws, means formed to serve as a guide along which said jaws are movable as a unit to pull the upper, and a handle for effecting relative closing movement of said jaws and for moving 30 the jaws along said guide to pull the upper.

7. A portable lasting tool for pulling a shoe upper manually over a last comprising a pair of upper-gripping jaws, a member formed to rest on the bottom of the shoe and also to serve as a guide along which said jaws are movable as a unit to pull the upper, a handle mounted to swing relatively to said member, and lever-and-link connections between said handle and one of the jaws for effecting relative closing movement of the 40 jaws and for thereafter moving the jaws along said guide to pull the upper.

8. A portable lasting tool for pulling a shoe upper manually over a last comprising a pair of upper-gripping jaws, a member formed to rest on the bottom of the shoe to serve as a hold-down for the margin of an insole and also formed to serve as a guide along which said jaws are movable as a unit to pull the upper, said member having a handle in fixed relation thereto, another 50 handle movably mounted on said member, and connections between said movable handle and the jaws for effecting relative movement of the jaws to grip the margin of the upper and for moving the jaws along said guide to pull the upper.

9. A portable lasting tool for pulling a shoe upper manually over a last comprising a pair of upper-gripping jaws, a member formed to rest on the bottom of the shoe and also to serve as a guide along which said jaws are movable as a unit in a 60 direction substantially perpendicular to the shoe bottom to pull the upper, a pair of handles arranged to extend generally heightwise of the shoe in the pulling of the upper, one of said handles being fixed relatively to said member and the other movable relatively to said member, and connections between said movable handle and one of the jaws for effecting relative closing movement of the jaws and for thereafter moving the jaws along said guide to pull the upper.

10. A portable lasting tool for pulling a shoe upper manually over a last comprising a pair of upper-gripping jaws, a member formed to rest on the bottom of the shoe and also to serve as a guide along which said jaws are movable as a unit 70

heightwise of the shoe to pull the upper, one of
said jaws being mounted to swing toward and
from the other jaw and having an arm extending
in angular relation to the path of pulling move-
5 ment of the jaws, a link connected to said arm, a
lever connected to said link and mounted to swing
in directions heightwise of the shoe, and a mov-
able handle connected to said lever for operating
10 said swinging jaw to grip the upper and for mov-
ing both jaws along said guide to pull the upper.

11. A portable lasting tool for pulling a shoe
upper manually over a last comprising a pair of
upper-gripping jaws, a member formed to rest on
the bottom of the shoe and also to serve as a guide

along which said jaws are movable as a unit
heightwise of the shoe to pull the upper, one of
said jaws being mounted to swing toward and
from the other jaw and having an arm extending
in angular relation to the path of pulling move-
ment of the jaws, manually operated mechanism
5 connected to said arm to cause the swinging jaw
to grip the upper and to cause the jaws to move
along said guide to pull the upper, and a spring
arranged to resist movement of the jaws along 10
said guide to insure the gripping of the upper
prior to such movement of the jaws.
